UNITED STATES PATENT OFFICE

2,484,294

DRAWING BOARD

Gerald L. Jean, Wells Beach, Maine

Application October 10, 1946, Serial No. 702,473

1 Claim. (Cl. 33—80)

1

This invention relates to new and useful improvements in drawing boards and more particularly to a small portable type of drawing board including improvements in the attachment or mounting of a straight edge element relative to the drawing or upper surface of the board, said straight edge being slidable from one edge of the board to the opposite edge thereof and always remaining parallel to said edges.

Another feature of this invention is to provide a board of this character whereon said straight edge can be raised slightly away from the drawing surface of the board thereby preventing the straight edge, when moved, from smearing ink work and also allowing paper to be placed under said straight edge and fastened to the drawing surface.

A further important feature is to provide a device of this character which is of simple and practical construction, efficient and reliable in operation, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of the invention.

Figure 2 is a bottom plan view of the invention with parts broken away to show the grooves for the endless cable.

Figure 3 is a fragmentary end view.

Figure 4 is a sectional view taken on line 4—4 in Figure 2.

Figure 5 is a sectional view taken on line 5—5 in Figure 2.

Figure 6 is an enlarged sectional view taken on line 6—6 in Figure 5, and

Figure 7 is an enlarged sectional view taken on line 7—7 in Figure 1.

Referring now to the drawing in detail, wherein for the purpose of illustration, I have disclosed a preferred embodiment of the invention, the numeral 5 represents an upper rectangular wooden slab affording a drawing surface and having a straight edge 6 movable thereon. A lower slab 7 of the same relative area as slab 5 is disposed under slab 5 and is secured thereto by screws 8 at each corner of the board. The heads 9 of said screws are countersunk in circular recesses 10 so that the screw heads offer no offensive roughened surface to the bottom of slab 7. At each corner of slab 5 and in the bottom

2

surface thereof are segmental recesses 11, and journaled on the screws 8 within the recesses 11 are horizontal pulleys 12, as shown in Figure 4.

The wooden slab 5 contains the straight edge attachment 6 and control mechanism therefor. For the purpose of this mechanism, the slab 5 is rabbeted at its lower side edges as at 12a, and a pair of brackets 13 are provided whose upper ends 13a are substantially channel shaped and face inwardly to grip the ends 14 of the straight edge. A pair of screws 14a extend through the brackets and into the straight edge. The bracket 13 has lower ends 15 that are bent inwardly and are slidable in the rabbeted lower side edges of the slab 5. Each bracket end 15 is provided with a pair of keyhole slots 16, with the larger ends 17 of said slots facing each other.

For the purpose of maintaining the straight edge element 6 in a horizontal position and permitting movement thereof from the upper edge of the board to the lower edge, a pair of cables 18 and 19 are used. These cables are extended around pulleys 12 at opposite corners of the board and lie in crossed diagonal grooves 19a and the rabbeted edges 12a in the bottom surface of slab 5. Each end of each cable is secured to a fastener 20 having a hollow end 21 in which the end of the cable is received and held therein by pressing portions of the fastener inwardly to bite into the cable as at 22. The outer end of the fastener material is bent angularly and formed with a flat head 23 insertable in a slot 16 for retaining the fastener in position. The fasteners 20 at opposite ends of cables 18 and 19 are placed in slots 16 at the upper edges of brackets 13 at opposite ends of straight edge 6 and the fasteners 20 at the other ends of said cables are placed in the lower slots 16 of the brackets at the opposite ends of the straight edge, to form an endless flexible connector as shown in Figure 2.

The brackets 13 fit snugly against the side edges of the board 5 and may be raised slightly relative thereto in order that the straight edge may be raised as before mentioned.

The straight edge is moved toward either the top or bottom edge of the board by grasping one end of the straight edge and sliding it up or down, the cables 18 and 19 equalizing the pulling force at the ends of the straight edge to prevent binding of the brackets 13 at the edges of the board.

In view of the foregoing description, taken in conjunction with the accompanying drawings, it is believed that a clear understanding of the construction, operation and advantages of the device

will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claim. The straight edge preferably has a transparent edge portion so that the draftsman may see the work therethrough.

What I claim:

A drawing board comprising an upper rectangular slab affording an upper drawing surface, said upper slab having crossed diagonal grooves and corner recesses in its bottom surface and being rabbeted at the lower portions of its side edges from one corner recess to the other on each side of the slab, a lower slab of the same shape and size as the upper slab secured to the under surface of the latter and closing the bottoms of said grooves, recesses and rabbets, a straight edge movable on said drawing surface and projecting beyond the side edges of the upper slab, a bracket carried by each end of the straight edge, said bracket having an inwardly facing channel shaped upper end receiving and secured to the end of said straight edge and a horizontal lower end portion extending into the adjacent rabbet and provided with a pair of oppositely fac-

ing keyhole slots whose larger ends are adjacent, the lower ends of the brackets being vertically movable in the rabbets to permit raising of the straight edge from the drawing surface, pulleys 5 journaled in the corner recesses, cables extending around said pulleys and through said grooves and rabbets and connected to the lower end portions of the brackets, and angular fasteners having horizontal arms secured to the ends of the cables 10 and having vertical arms provided with end heads retainingly engaged in the keyhole slots of the brackets.
